STRINGED MUSICAL INSTRUMENT
AND BOW

John A. Graydon, Hawthorne, N. J.

Application January 4, 1947, Serial No. 720,213

10 Claims. (Cl. 84—274)

1

This invention relates to stringed musical instruments, and more particularly to such instruments of the viol class including the bow for playing same.

Stringed musical instruments of the viol class are normally provided with four strings which are stretched over a resonance box and a suitable finger board to a head upon which the strings are secured by pegs. A bridge supports the strings upon the resonance box, the bridge usually being arched in a well known manner which disposes the strings of the instrument in such a way that a conventional bow may sound only two of such strings simultaneously.

The acoustics of instruments of this class are extremely complex. Certainly, so far as the elementary principles which govern its action are concerned, it follows sufficiently familiar laws. The different notes of the scale are produced by vibrating strings differing in weight and tension, and varying in length under the hand of the player. The vibration of the strings are conveyed through the bridge to the resonance box or body of the instrument, which fulfills the function of a resonator in reinforcing the notes initiated by the strings. When we attempt to define the peculiar character of the tone of the instruments of this family and the causes of such tone, the great range and variety of said tone obtained in different instruments of this type, the extent to which those qualities can be controlled by the bow of the player, and the mode in which they are influenced by minute variations in almost every component part of the instrument, we find ourselves faced by a series of problems which so far have defied anything but a partial solution. We know, of course, that the character of the tone is a function, among many other things, of the range of action of the bow in producing certain chords. A very limited range has in the past been imposed by the peculiar structure of the conventional viol type instrument and bow. However, I have discovered a novel structure which increases the range of action of the bow for this type of instrument whereby any desired combination of strings may be sounded simultaneously and thus whereby chords and tones may be produced which heretofore have been impossible.

Various further and more specific features and advantages of the invention will clearly appear from the detailed description given below taken in connection with the accompanying drawings which form a part of this specification and illustrate, by way of example, a preferred arrange-

ment for carrying out the invention. The latter consists of such novel combination of features as may be shown and described in connection with the device herein disclosed.

5 In the drawings:

Figure 1 is a perspective view of a novel violin and bow illustrating one embodiment of the present invention;

10 Fig. 2 is a side view partly in section and with parts broken away illustrating the novel violin bow in cooperation with a novel violin embodying the present invention;

Fig. 3 is a partial side view partly in section taken on line 3—3 of Fig. 1;

15 Fig. 4 is a sectional view taken on line 4—4 of Fig. 1;

Fig. 5 is a sectional view taken on line 5—5 of Fig. 1; and

20 Fig. 6 is a view taken on line 6—6 of Fig. 3 illustrating retaining means for holding the novel violin bow in slidable relation to the violin.

The invention disclosed herein comprises in general means for playing simultaneously and selectively one or more of the strings of an instrument of the viol class such as a violin. The means for accomplishing this comprises, in the form shown, a slanted or inclined bridge upon the violin for supporting the strings wherein one string may be held at the peak of the bridge and the remaining strings are situated at intervals down the sloping surface thereof. The strings thus are situated, at the bridge, at differing distances from the resonance box of the instrument and are disposed for engagement with individual subsidiary bows, one for each string. A novel bow is provided which is constituted by a plurality of said subsidiary bows. The number of the latter is similar to the number of strings upon the instrument, each subsidiary bow having a string corresponding thereto which is to be sounded thereby. The shafts of each of the subsidiary bows may be held in a predetermined position relative to the string corresponding thereto by means, for example, of a rack or support member which adapts said shaft for sliding movement at the proper spaced relationship to each corresponding string. Each subsidiary bow is held out of engagement with its corresponding string by suitable resilient means. Manually or digitally operable means such as finger keys are provided, one for each subsidiary bow, by which each bow may be angularly shifted selectively to engage the corresponding string thereof.

45 50 Referring to the drawings in further detail,

the novel musical device is constituted by, for example, a stringed instrument 10 which, as above mentioned, preferably is of the viol family, and in the form shown is similar to a conventional violin with certain exceptions to be set forth below. A novel bow 11 is employed for sounding the strings in a manner also to appear below.

The stringed instrument 10 is constituted by a resonance box 12 having a neck 13 and a peg box 14, all of which may be of conventional violin construction.

The violin 10 is provided with four strings 15, 16, 17 and 18 which may be tuned in a normal manner, for example, to *g*, *d'*, *a'* and *e''*. The strings may have a conventional range from *g* to *c'''*.

In order to position the strings 15, 16, 17 and 18 in such a manner that they may be properly located for cooperation with the novel bow 11, a novel bridge structure is provided which comprises a slanted or inclined bridge 19 which is adapted for holding the strings at differing distances from the resonance box 12, for example, whereby one of said strings, as 15, is held at the peak of the bridge and the remaining strings, 16, 17 and 18 are situated at intervals down the sloping or inclined surface thereof. It is desirable that the spacing between the strings at the bridge 19 be uniform.

With the strings of the violin situated as above described, they are located at proper levels whereby each may be engaged and sounded by an individual or a subsidiary bow in a manner to appear more fully hereinafter.

The multi-part bow 11 is constructed and arranged whereby each subsidiary bow may sound one of the above mentioned strings. As shown in particular in Fig. 2, the multi-part bow 11 is preferably constituted by a plurality of subsidiary bows 11a, 11b, 11c and 11d. These bows are superposed relative to one another by means of, for example, a U-shaped bracket member 20 which provides, by means of vertical arms 20a, 20b thereof a double bearing surface for each of said subsidiary bows. The member 20 preferably is situated at the base of the bow, that is, at the portion which is to be grasped by the hand of the musician. Each of the subsidiary bows 11a to 11d is constituted by a rigid stick or shaft member which preferably is of oval or elliptical cross section along that portion of the length thereof which is adjacent to the hair or sounding member. The sticks or shaft members of the subsidiary bows are designated respectively 21, 22, 23 and 24 (Fig. 2). The respective hair strands or string-sounding members for the subsidiary bows are indicated at 25, 26, 27 and 28 respectively. Each hair strand of each subsidiary bow is stretched between a suitable head and a hair strand holder preferably in such a manner that the plane of the hair strand is substantially parallel with the major axis of the oval cross section of the respective stick or shaft member thereof. This is illustrated in Fig. 3 wherein the plane of each of the hair strands is horizontal and said major axis of the cross section of each subsidiary stick also is horizontal. The reason for this is to provide desired strength and flexibility to each of the subsidiary shafts or sticks, thus providing necessary tension to each of the subsidiary hair strands. Hair strand holders of each of the subsidiary bows 11a, 11b, 11c and 11d are respectively indicated at 29, 30, 31 and 32.

Each of the subsidiary bows is adapted for being shifted angularly about the longitudinal axis

thereof in order to move each of the hair strands thereon from a normally inactive position into engagement with the string which corresponds thereto whereby the latter may be sounded. Each 5 of the subsidiary bows normally is maintained in an inactive position against a limit stop by suitable resilient means. In the form shown, for example, the bow 11d is provided with a limit stop 33 which preferably is constituted by a suitable 10 collar (Fig. 2) having a small finger thereon as at 33a. The latter may be adapted for contacting a limit, such as the next adjacent shaft member 23, whereby angular motion of the shaft 24 of bow 11d may be arrested. Suitable yielding or resilient means may be provided for urging the 15 limit stop 33 against its limit, i. e., the next adjacent stick comprising, for example, a coil spring 34 which may surround the shaft 24 adjacent one of the vertical arms such as 20b of the U-shaped member 20. Analogous limit stops are provided for the bows 11a, 11b and 11c respectively as at 35, 36 and 37. Also, analogous resilient means for said bows 11a, 11b and 11c may be provided as indicated at 37, 38 and 39.

The distinctive quality of the musical tones of the instruments of the viol class, and in particular of the violin, is generally admitted to be due largely to its richness in the upper harmonic or partial tone superimposed on the fundamental 25 notes produced by the simple vibrations of the strings. The characteristic tone and its control by the player are undoubtedly conditioned in the first place by the peculiar response of the vibrating strings of the action of the rosined bow. 30 This takes the form not of a symmetrical oscillation but of a succession of alternating bound and free movements, as the string adheres to the bow according to the pressure applied and, releasing itself by its elasticity, rebounds. Control 35 of the pressure applied to each string is accomplished by the fingers which act against the tension upon each of the subsidiary hair strands, and also against the resilient members or coil springs 34, 37, 38 and 39.

40 Suitable means are provided for selectively engaging any one or more of the subsidiary bows with its corresponding string comprising in the form shown digitally operable members or finger keys which are attached to respective of the angularly shiftable subsidiary bows. Each of the sticks or shaft members 21, 22, 23 and 24 is provided respectively with finger keys 40, 41, 42 and 43. Said keys are, of course, preferably situated at the handle or base of the multi-part bow and, 45 in the form shown, they are mounted between the arms 20a and 20b of the U-shaped member 20.

It will be seen that in view of the necessity for the player to operate said keys by his fingers, the manner of grasping the multi-part bow is considerably different from that of a conventional bow, and axial thrust to the multi-part bow must be imparted in a different way.

In the form shown, the thrust is communicated to the multi-part bow through the intermediary of the thumb of the player with the aid of a thumb sleeve 44 which may be pivotally mounted to the U-shaped member 20. The thumb sleeve is adapted for surrounding substantially all of the thumb of the player whereby an adequate thrust 50 is communicable to the bow.

As illustrated in Fig. 1, there is no interconnection between the subsidiary bows at the heads thereof. Preferably the only interconnection between said subsidiary bows exists by virtue of the 55 U-shaped member 20. This, of course is neces-

sary because it would be impossible to insert the heads of the bows in between the strings of the violin if some interconnection existed therebetween. Preferably, no interconnection is formed between the subsidiary bows throughout the lengths thereof except as above mentioned.

Suitable means must be provided for supporting the individual subsidiary bows in an operative and slideable position relative to their corresponding strings. In the embodiment shown, with particular reference to Figs. 2 and 3, the means for supporting the individual subsidiary bows in slideable relationship to their corresponding strings, is constituted by a rack member 45 having a plurality of fingers equal in number to the number of subsidiary bows. Such fingers are indicated as at 46, 47, 48 and 49.

It is desirable for each of the subsidiary bows to be completely surrounded by the respective supports therefor but, of course, adapted for sliding movement therethrough. The rack 45 and its fingers provide such support, for example, in cooperation with a movable retaining finger 50 (Fig. 3) which is adapted for closing the mouth which is formed by the above identified fingers 46-49. An upper finger 51 may be formed upon the rack for cooperating with the finger 46 and the retaining finger 50 whereby the uppermost stick or shaft 21 also is surrounded. The next lower stick 22 is slideable between the fingers 46 and 47. The stick 23 is slideable between the fingers 47 and 48 and the stick 24 is slideable between fingers 48 and 49. The retaining finger 50 may be angularly shifted away from the position as shown in Fig. 3 whereby the subsidiary bows may be disengaged from the rack. As shown in Fig. 6, the active position of the retaining finger 50 is indicated in solid lines, and the disengaged or inactive position is indicated in broken lines. A manually operable arm 52 may be provided for communicating an angular thrust to said retaining fingers whereby it may be shifted to its inactive position through the intermediary of a shaft 53 which may be hinged as at 54 and 55. Suitable resilient means such as coil spring 56 (Fig. 3) may be employed for urging the shaft 53 to a normal active position whereby the retaining finger is in the position shown in solid lines in Fig. 6.

With reference to the finger board of the novel violin, it is desirable for the peg box 14 to be of conventional design with a so-called nut portion as at 57. The latter constitutes a bearing surface for the strings of the instrument and should be in a plane which is parallel to that of the main body portion of the violin. That is, it is desirable for the bearing surface or nut 57 to be substantially parallel to the plane which is formed by the upper surface of the resonance box 12. As shown in Fig. 4, the plane of said nut 57 would be parallel with the upper surface of the neck 13 and is horizontal as viewed in Fig. 1. In view of the fact that the strings 15, 16, 17 and 18 are mounted upon the specially shaped or inclined bridge 19, it is necessary to provide a novel finger board 58 therefor. It is desirable for the finger board to be substantially at a uniform distance from each of the strings at the areas thereof which are immediately beneath each of said strings. The surface which is defined by the strings stretched between nut 57 and bridge 19 is not a plane surface but rather is substantially a twisted or somewhat helical surface. Consequently, the finger board 58 preferably should be of a corresponding shape with the area of the finger board directly

beneath each of the strings being substantially at a uniform distance from each of said strings throughout the length thereof. The sectional views of the finger board 58 as indicated in Figs. 4 and 5 indicate the change in cross-sectional shape and inclination of the finger board as it progresses from the peg box down to a point near the bridge 19.

In order to insert the multi-part bow 11 into an operative relationship to the violin 10, it is necessary to shift the retaining finger or bar 50 from the position shown in solid lines in Fig. 6 to the position shown in broken lines. At this point the head or upper extremity of the multi-part bow may be associated with the rack 45 as shown in Fig. 3. After the bow has been so positioned, the retaining finger 50 may be shifted angularly back to its initial position where it will be interposed between the shafts of the subsidiary bows and the respective hair strands thereof.

By operating the finger keys 40-43 any one or combination of the strings 15-18 may be sounded when the box is shifted axially.

It is, of course, possible instead of employing a rack as indicated in particular in Fig. 3 to employ analogous support means, for example, which may be associated, for example, with the bridge 19. The rack 45 preferably is secured to the finger board 58, for example, by means of an arm 45a which extends axially of the violin and which may be attached to said finger board as by suitable screws.

While the invention has been described with respect to a preferred example which has given satisfactory results, it will be understood by those skilled in the art after understanding the invention that various changes and modifications may be made without departing from the spirit and scope of the invention, and it is intended, therefore, in the appended claims, to cover all such changes and modifications.

What is claimed as new and is desired to be secured by Letters Patent is:

1. In a violin having a sounding box, an inclined bridge, the strings of said violin being held thereon in spaced relationship at different levels relative to the sounding box, a multi-part bow having a plurality of subsidiary bows each being adapted for sounding a corresponding string of the violin, and a like plurality of support members mounted adjacent said bridge for supporting corresponding of said subsidiary bows at levels adjacent the strings corresponding thereto.
2. In an instrument of the viol class having a plurality of strings stretched over a resonance box, means mounted upon the box for holding successive of said strings at successively greater distances from the box, a multi-part bow comprising a like plurality of subsidiary bows each adapted for sounding corresponding of said strings, and a like plurality of support members mounted on the box for holding corresponding of said subsidiary bows at levels adjacent corresponding of said strings.
3. In a musical instrument of the class described having a plurality of strings, a bracket member having a like plurality of retaining fingers mounted upon said instrument, and a multi-part bow having a like plurality of subsidiary bows adapted for operatively engaging corresponding of said strings, said subsidiary bows being held by corresponding of said retaining fingers.
4. In a musical instrument having a resonance box and a plurality of strings adapted to be

sounded by sounding members, a bridge for holding said strings each at a different distance from the box, a multi-part sounding member comprising a like plurality of subsidiary sounding members for sounding corresponding of said strings, and means for supporting corresponding of said subsidiary sounding members at correspondingly differing distances from the resonance box.

5. In a musical instrument having a resonance box and a plurality of strings adapted to be sounded by sounding members, a bridge for holding said strings each at a different distance from the resonance box, a multi-part sounding member comprising a like plurality of subsidiary sounding members, means for supporting each of said subsidiary members for sliding movement adjacent the corresponding string thereof, means upon said multi-part sounding member for yieldingly urging each of said subsidiary members out of engagement with its corresponding string, and digitally operable means upon said multi-part sounding member for selectively engaging each of said subsidiary members with its corresponding string.

6. In a musical instrument having a plurality of strings stretched over a resonance box and a neck member, a bridge for holding said strings each at a different distance from the resonance box, a nut having a bearing surface substantially parallel to the plane of the box, a finger board upon said neck extending from said nut to a position adjacent said bridge, the area of said board beneath each of the strings being substantially at a uniform distance therefrom, a multi-part bow comprising a like plurality of subsidiary bows for sounding corresponding of said strings, means upon said box for supporting corresponding of said subsidiary bows for sliding movement at differing distances therefrom corresponding to said distances of said strings therefrom.

7. In a bow for sounding the strings of a musical instrument, a plurality of subsidiary bows, a common support for said subsidiary bows, the latter being mounted for angular movement relative to said support, and a like plurality of digitally operable members for angularly moving corresponding of said subsidiary bows, said members being operable singly or in combination with any other such members.

8. A violin for use with a multi-part bow hav-

ing a plurality of subsidiary bows, said violin having a sounding box, and a like plurality of strings including in combination: an inclined bridge, the strings of the violin being held thereon in spaced relationship at different levels relative to the sounding box; the subsidiary bows each being adapted for sounding a corresponding string of said violin; and a like plurality of support members mounted adjacent said bridge for supporting corresponding of the subsidiary bows at levels adjacent the strings corresponding thereto.

9. In an instrument of the violin class having a plurality of strings stretched over a resonance box and adapted for use with a multi-part bow having a like plurality of subsidiary bows; a bridge mounted upon the box for holding successive of said strings at successively greater distances from the box; the subsidiary bows each being constructed and arranged for selectively sounding corresponding of said strings; and a like plurality of support members mounted on the box for holding corresponding of the subsidiary bows at levels adjacent corresponding of said strings.

25. 10. In a bow for sounding the strings of a musical instrument, a plurality of subsidiary bows; a common support for said subsidiary bows, the latter bows being mounted for angular movement relative to said support; and a like plurality of digitally operable members associated with corresponding of said subsidiary bows for selectively angularly shifting one or more thereof.
